US0D1049924S

(12) **United States Design Patent** (10) Patent No.: **US D1,049,924 S**
(45) Date of Patent: ** Nov. 5, 2024

(54) **GOLF CART**

(71) Applicant: **MARSHELL ELECTRIC VEHICLE SHENZHEN CORPORATION**, Shenzhen (CN)

(72) Inventors: **Xiaomin Xie**, Zhaoqing (CN); **Qiang Chen**, Zhaoqing (CN); **Jiagao Wei**, Hechi (CN)

(73) Assignee: **MARSHELL ELECTRIC VEHICLE SHENZHEN CORPORATION**, Shenzhen (CN)

(**) Term: **15 Years**

(21) Appl. No.: **29/950,510**

(22) Filed: **Jul. 3, 2024**

(51) LOC (14) Cl. **12-02**
(52) U.S. Cl. USPC **D12/16**
